UNITED STATES PATENT OFFICE.

EMMET H. McMURRY, OF MARIANNA, ARKANSAS, ASSIGNOR OF ONE-FOURTH TO JAMES L. WEST, ONE-SIXTH TO HAL S. MIXON, ONE-SIXTH TO ROBERT L. MIXON, AND ONE-SIXTH TO LARIMORE ROBINSON, ALL OF MARIANNA, ARKANSAS.

BALING-PRESS.

No. 883,145.

Specification of Letters Patent. Patented March 24, 1908.

Application filed June 14, 1907. Serial No. 379,065.

To all whom it may concern:

Be it known that I, EMMET H. McMURRY, a citizen of the United States, residing at Marianna, in the county of Lee and State of 5 Arkansas, have invented a new and useful Baling - Press, of which the following is a specification.

This invention relates to baling presses and is more particularly an improvement 10 upon the apparatus described and claimed in Patent No. 855,015, granted to me on May 28, 1907.

The invention resides especially in improved power mechanism whereby the rotation of a driving element will be caused to 15 operate mechanism to produce a preliminary compression of the hay or other material supplied to the press and cause said material to be directed into the path of the main 20 plunger or follower which subsequently completes the compression of the material within the pressure box.

Another object is to simplify the construction of power mechanism for producing the 25 above result and to provide such mechanism which can be conveniently operated, will not easily get out of order and which can be readily repaired in the event of the breaking of any of the parts.

With these and other objects in view the invention consists of certain novel features 30 of construction and combinations of parts which will be hereinafter more fully described and pointed out in the claims.

In the accompanying drawings is shown 35 the preferred form of the invention.

In said drawings: Figure 1 is a plan view of the mechanism embodying the present improvements, the press being shown in connection therewith, and portions thereof being 40 in section. Fig. 2 is a longitudinal section through the apparatus. Fig. 3 is a central transverse section through the press. Fig. 4 is a section on line $x-x$, Fig. 3. Fig. 5 is a 45 plan view of the power transmitting devices of the preliminary compressing mechanism. Fig. 6 is a transverse section through the guide trough of said mechanism, and showing the deflecting blocks in end elevation. Fig. 7 is a detail view of a portion of one of 50 the deflecting blocks and the clutch members coöperating therewith. Fig. 8 is a transverse section through a portion of the trough and showing the guides of the main plunger.

Fig. 9 is a view partly in section and partly 55 in elevation of the connection between the operating element and the clutch actuating cable, the parts being shown in the position assumed at the beginning of the movement of said mechanism. Fig. 10 is a view similar 60 to Fig. 9 showing the positions assumed by the parts upon the completion of the movement of the clutch actuating mechanism.

Referring to the figures by characters of reference, 1 designates a press box such as 65 shown and described in my patent before mentioned, the same being provided adjacent its inlet end with laterally extending rails 2 secured to laterally extending side walls 2^a. A sliding base 3 is mounted on 70 these rails and between the walls 2^a and provided at its ends with upstanding walls or followers 4 and 4^a suitably braced. One or more slotted guides 5 are disposed adjacent and above the feed end of the press box and 75 movably mounted within these guides are upwardly extending projections 6 formed upon a partition 7. This partition is mounted to travel above the base 3 and has depending legs 8 designed to project through 80 slots 9 formed longitudinally within the base. Each leg extends upward from a carriage 10 provided with anti-friction rollers 11 adapted to travel within channel bars 12 disposed beneath the base. It is obvious that 85 when the follower 4 is disposed adjacent the inlet end of the press box and the follower 4^a is located at a distance therefrom the partition 7 is free to travel within the guides 5 and the slots 9 and this partition is designed to 90 aline with either of the walls of the press box while one of the followers 4 and 4^a is alining with the other wall thereof.

Extending from the feed end of the press box is a trough-like structure 13 which, as 95 shown in Figs. 6 and 8, is provided with a longitudinal slot 14 in the top thereof in which is mounted a slide 15 to which is fastened the stem 16 of plunger 17. Extending longitudinally from the end of the trough 13 100 are preferably two beams 18 between which is secured a block 19 constituting the bearing for a pulley 20. A spring 21 connects the stem 16 with the fixed block 19 so that the plunger 17 is held normally withdrawn from 105 the feed end of the press box 1. A cross beam 21' is connected to the terminals of the beams 18 and a stud 22 extends upward

from their points of connection and constitutes the pivot for a sweep 23. A roller 24 is journaled in each end of the sweep and these rollers are designed to successively swing 5 into contact with the concave head 25 of a pitman 26 pivoted to one end of the stem 16. This head 25 has an angular arm 27 extending therefrom and under the path of the rollers 24 and a guide stud 28 extends downward 10 from the arm 27 and is designed to travel within an arcuate slot 29 formed in a roller guide 30 which is secured to the beams 18 and 21'. An arm 31 extends from each end of the sweep below and beyond the rollers 15 upon the sweep and, as shown in Figs. 9 and 10, this arm is formed preferably with a concave face 32 for the purpose hereinafter disclosed.

Suitably supported beneath the base 3 are 20 pulleys 33 which serve to support and guide opposite portions of a cable 34 constituting power transmitting means. The ends of this cable are fastened to opposite end portions of the base 3 preferably by means of hangers 36 25 extending downward from the base. The intermediate portion of the cable forms a loop which extends partly around and is supported by the pulley 20 hereinbefore referred to. This cable 34 extends through the 30 trough 13 and above deflecting blocks 37 disposed within the trough adjacent the base 3 and those ends of the blocks nearest the pulley 20 are inclined as shown particularly at 38. Secured to the cable 34 between 35 each pulley 33 and the pulley 20 is a block 39 to which is pivotally connected preferably two hooks 40 constituting clutch members. The two blocks 39 and their hooks are so disposed that while one of the blocks is reaching 40 the limit of its movement in one direction the hooks of the other block 39 move upward on one of the deflecting blocks 37. A clutch member in the form of a cross head 41 is slidably mounted within the trough and 45 above the cable 34 and this cross head is provided with an extension 42 located below the plane occupied by the cable 34 and fastened by means of a cable 43 to a coiled spring 44 extending under the press box and designed 50 to hold the cross head normally positioned above and between the blocks 37. Another cable 45 is fastened to the extension 42 of the cross head and extends under the pulley 20 and partly around a pulley 46 located adjacent 55 one of the terminals of an arcuate guide rail 47 secured to the beams 18 and 21. This rail has a curved slot 48 in which a slide 49 is mounted to travel and said slide has a hanger 50 to which the end of cable 45 is secured. An arm 51 is pivotally connected to 60 the slide 49 and carries a roller 52. A spring 53 is fastened to the slide and holds arm 51 normally in contact with a stop pin 54 carried by the slide. When the arm is in its 65 normal position the roller 52 is supported

within the path of the arms 31 on the sweep 23. A deflecting roller 55 is mounted within the guide rail 47 adjacent that end thereof farthest removed from the pulley 46. It will of course be seen by referring to the drawing that the two arcuate guides 30 and 47 are formed along lines concentric with the stud 22, the guide 47, however, being located a greater distance from the stud than the guide 30 so that the rollers 24 are free to rotate along the concave face of the guide 47 without being retarded thereby.

The mechanism herein described is designed to produce a double compression of material such as hay or straw which may be fed to the press. The first of these compressions takes place between one of the followers 4 and 4^a and the movable partition 7, while the second or final compression occurs within the box 1 and is produced by the plunger 17. As has heretofore been stated the base 3 is mounted to slide laterally in relation to the press box and when in either of its positions the partition 7 alines with one of the side walls of the press box while either the end wall 4 or the wall 4^a alines with the other side wall of the press box. For example, if the parts are in the positions disclosed in Fig. 1 the material to be baled is fed between the walls 2^a and the wall 4 and 90 partition 7. The sweep 23 is set in motion by horse power or in any other preferred manner and as one of its rollers swings toward the beams 18 it will come into contact with the concave face of head 25 and cause the pitman 26 to force the stem 16 and plunger 17 forward into the press box so that any material in the path of the plunger will be directed into the box. When the head 25 reaches the limit of its movement along 95 the arcuate guide 30 the roller 24 will move off of the head and spring 21, which is placed under stress during the forward movement of the plunger, promptly pulls backward on the stem 16 so as to quickly return the plunger 100 to its initial position and to bring the head 25 to a point where it can be contacted by the next roller 24 and the operation above described repeated. As soon as the plunger returns to its initial position in the manner 105 described one of the arms 31 moves against the raised roller 52 on slide 49, as shown in Fig. 9, and therefore the slide is caused to move forward within the slot 48 and to pull upon the cable 45. This will cause the cross 110 head 41 to pull forward and as this cross head is located normally above the blocks 37 and between said blocks and the base 3, as shown in Fig. 1, it is apparent that during this movement it will be brought into engagement with those hooks 40 which are resting upon the block 37. This will be apparent by referring to Fig. 6 wherein the cross head is shown back of and in position 115 to engage hooks located upon one of the de- 120

flecting blocks. As soon as the hooks 40 are engaged by the cross head they are drawn therewith and cause the cable 34 to be moved in the direction of its length. The base 3 will therefore be shifted longitudinally so as to draw the follower 4 toward the inlet end of the press box and the partition 7 will also be free to move across said inlet end until stopped by the extensions 6 coming into contact with the opposite ends of guides 5. The further movement of the base 3 and follower 4 will be independent of the partition 7 because of the slots 9 which are employed and therefore the material which has been placed between the partition and the follower 4 will be compressed in the path of the plunger 17, this compression continuing until the follower 4 is brought into position in alinement with the nearest side wall of the press box. As soon as this compression between the partition 7 and the follower 4 has been accomplished the slide 49, which has been moving within the slot 48, is brought under the roller 55 and said roller will serve to press the arm 51 downward so as to withdraw the roller 52 from the path of arm 31. Said arm will therefore be free to continue its movement with the sweep while the spring 44 which has been tensioned as a result of the movement of the cross head 41 and slide 49, will return the slide and cross head to their initial positions. During this return movement of the cross head it will leave those hooks 40 which were in engagement therewith and will travel back to its initial position, passing over the other set of hooks 40 which, in the meantime, have been brought into position upon the other deflecting block 37. The material to be baled can then be placed between the partition 7 and the follower 4^a and upon the repetition of the operation above described this material will be initially compressed in the path of the plunger 17.

It will be seen that the mechanism described is very simple, durable, and efficient and produces an initial as well as a final compression of the material in an expeditious manner without adding to the power required to perform either of the operations.

What is claimed is:

1. In a baling press the combination with a press box, and separate means for producing an initial and a final compression of material in the press box; of a revolute actuating device disposed to actuate one of said means to produce two final compressions during each rotation of said device, a slideable cross head disposed to be reciprocated by said device, and means disposed to be alternately engaged by opposite portions of said cross head to shift the initial compressing means twice during each rotation of the actuating device.
2. In a baling press the combination with

initial compressing means including simultaneously movable followers; of a flexible power transmitting device connected to the followers and having an intermediate loop, means designed to alternately engage opposite portions of the loop, and revolute means for actuating said engaging means during a part of the rotation of said revolute means.

3. In a baling press the combination with a press box, a plunger mounted to reciprocate therein, and laterally movable followers designed to produce an initial compression of material in the path of the plunger; of a revolute actuating device disposed to actuate the plunger to produce two compressions during each rotation of said device, a slide in the path of said device, a clutch member movable therewith, and means disposed to be alternately engaged by said clutch member to shift the followers twice during each rotation of the actuating device.

4. In a baling press the combination with a press box, a plunger designed to reciprocate therein, and followers adjacent the press box and disposed to produce an initial compression of material in the path of the plunger; of a revolute actuating device, means operated thereby for actuating the plunger, a flexible power transmitting device connected to the followers and having a loop guided adjacent the plunger, clutch members carried by opposite portions of said loop, a cross head designed to alternately engage said members to actuate the power transmitting device and shift the followers, and means operated by the actuating device for shifting the cross head during a portion of the rotation of said device.

5. In a baling press the combination with a press box, a plunger mounted to reciprocate therein, followers designed to produce an initial compression of material in the path of the plunger; of a revolute actuating device, means operated thereby for reciprocating the plunger during a portion of the rotation of the device, a flexible power transmitting device connected to the followers forming an intermediate loop, clutch members carried by the loop, a cross head disposed to alternately engage the clutch members, means operated by the actuating device for shifting the cross head to actuate the clutch members, and deflecting means for directing the clutch members successively into the path of the cross head.

6. In a baling press the combination with initial compressing means including simultaneously movable followers; of a flexible power transmitting device connected to the followers and having an intermediate loop, clutch members carried by opposite portions of the loop, a cross head designed to alternately engage said members, and revolute means for actuating the cross head during a part of the rotation of said means.

7. In a baling press the combination with means for producing an initial compression of material, said means including simultaneously movable followers; of mechanism for actuating said means and comprising a flexible power transmitting device connected to the followers and having an intermediate loop, clutch members carried by opposite portions of the loop, a cross head designed to alternately engage the clutch members, means for successively directing the clutch members into the path of the cross head, and means for reciprocating the cross head.

8. In a baling press the combination with means for producing an initial compression of material, said means including simultaneously movable followers; of mechanism for actuating said means and comprising a flexible power transmitting device connected at its terminals to the followers and having an intermediate loop, pivoted clutch devices carried by opposite portions of the loop, a cross head, means for successively directing the clutch members into the path of the cross head, revolute actuating means, and means operated by the rotation thereof for shifting the cross head out of normal position.

9. In a baling press the combination with means for producing an initial compression of material, said means including simultaneously movable followers; of a flexible power transmitting device connected to the followers and having an intermediate loop, hooks movably connected to and designed to travel with opposite portions of the loop, a cross head, and means for directing the hooks successively in the path of the cross head, and means for reciprocating the cross head to actuate the hooks and loop.

10. In a baling press the combination with means for producing an initial compression of material, said means including simultaneously movable followers; of a flexible power transmitting device connected to the followers and having a looped intermediate portion and having hooks movably connected to and disposed to travel with opposite portions of the loop, a cross head, yieldable means for holding said head normally in a predetermined position, stationary means for successively directing the hooks into the path of the cross head, and means for shifting the cross head out of normal position.

11. In a baling press the combination with compressing means, said means including simultaneously movable followers; of a flexible power transmitting device connected to the followers and having an intermediate looped portion, clutch members carried by opposite portions of the loop, a cross head disposed to successively engage said clutch members, a slide connected to and disposed to actuate the cross head, a sweep, means upon the slide for engaging the sweep during a portion of the movement thereof, and

means for returning the slide and cross head to their initial positions and release it from the seat.

12. In a baling press the combination with compressing means including simultaneously movable followers; of mechanism for actuating said means and comprising a flexible power transmitting device secured to the followers and having a looped intermediate portion, clutch members carried by opposite portions of the loop, a spring controlled cross head disposed to alternately engage the clutch members during successive movements in one direction, and means for shifting the cross head out of normal position.

13. In a baling press the combination with compressing means including simultaneously movable followers; of mechanism for actuating said means and comprising a flexible power transmitting device connected to the followers and having a looped intermediate portion, clutch members carried by opposite portions of the loop, a cross head designed to alternately engage the clutch members during the successive movements of the cross head in one direction, and means for reciprocating the cross head.

14. In a baling press the combination with compressing means including a shiftable base and a follower carried thereby; of a flexible power transmitting device connected to opposite portions of the base and having a looped intermediate portion, clutch members carried by opposite portions of the loop, a cross head designed to alternately engage the clutch members during the successive movements of the cross head in one direction, and means for reciprocating the cross head.

15. In a baling press the combination with compressing means including a shiftable base and a follower carried thereby; of a flexible power transmitting device connected to the end portions of the base and having an intermediate looped portion, clutch members carried by opposite portions of the loop, a cross head disposed to alternately engage the clutch members during the successive movements of the cross head in one direction, yieldable means for holding the cross head in a predetermined position, a sweep, means engaged thereby for actuating the cross head in one direction, and a release device for freeing said means from the sweep during the movement thereof.

16. In a baling press the combination with compressing means including a shiftable base and a follower movable therewith; of a flexible power transmitting device connected to the end portions of the base and having a looped intermediate portion, clutch members carried by opposite portions of the loop, a cross head disposed to alternately engage the clutch members during the successive movements of the cross head in one direction, yieldable means for holding the cross head

normally in a predetermined position, an arcuate guide, a slide mounted thereon and connected to the cross head, a sweep, a sweep engaging device upon the slide, and means 5 for shifting said device out of engagement with the sweep at a predetermined point during the movement thereof.

17. In a baling press the combination with a press box, a plunger mounted to reciprocate therein, and laterally movable followers 10 adjacent the press box for producing an initial compression; of arcuate guides, a pitman connected to the plunger and mounted to

travel upon one of the guides, a slidable member upon the other guide, means actuated thereby for shifting the followers, and a sweep disposed to successively engage and release the pitman and slidable member. 15

In testimony that I claim the foregoing as my own, I have hereto affixed my signature 20 in the presence of two witnesses.

EMMET H. McMURRY.
